UNITED STATES PATENT OFFICE.

WILLIAM B. MCLEAN, OF HENSALL, ONTARIO, CANADA.

STOVEPIPE-THIMBLE.

No. 894,455.

Specification of Letters Patent.

Patented July 28, 1908.

Application filed March 30, 1907. Serial No. 365,592.

To all whom it may concern:

Be it known that I, WILLIAM B. MCLEAN, a subject of the King of Great Britain, and a resident of Hensall, in the county of Huron, 5 in the Province of Ontario, Canada, have invented a new and useful Improvement in Stovepipe-Thimbles, of which the following is a specification.

This invention relates to a thimble or 10 sleeve which extends through a wall or ceiling, particularly around a stove pipe where the latter extends through the wall or ceiling.

The objects of this invention are;—to provide a device that will completely prevent 15 any excess of heat in the pipe from injuring or otherwise affecting the surrounding wall or ceiling, or the carpet on the floor of the room above the ceiling, and thus provide a fire proof stove pipe thimble; one that will 20 completely prevent any possibility of the dust in one room passing into the adjoining room into which the thimble opens, thus rendering the stove pipe thimble dust proof; one that is perfect in regulation because it 25 can be readily, easily and instantly adjusted by a person in either room or compartment into which it opens, to completely close the passage therethrough from one room into the other; one in which there is an air space be- 30 tween the stove pipe and the outside cylinder or barrel of the thimble, to convey the heat from one apartment to the other, and when one end of the thimble opens into a chimney or extends through an outside wall, 35 provides ventilation; and one which is pro- vided with registers at each end to regulate the passage of heat from one compartment to another or to regulate ventilation; and at the same time provide a neat, simple strong 40 and durable device, one that will be economical to manufacture, thus insuring its success commercially as well as for efficiency when in practical use.

With the above and other objects in view, 45 which will more clearly appear as the nature of the invention is better understood; the same consists in the novel construction combination and arrangement of parts which will be hereinafter first fully set forth and de- 50 scribed and then pointed out in the claims, reference being had to the accompanying drawings wherein;—

Figure 1. is a central cross sectional view 55 in perspective of a double barrel or cylinder stove pipe thimble illustrating my invention. Fig. 2. is a detail central cross sectional view

in perspective of one of the registers. Fig. 3. is a detail central cross sectional view in perspective of the detachable head or end of the stove pipe thimble. Fig. 4. is an end view of the thimble. In this view one half of the end cover is cut away. Fig. 5. is a central cross sectional view of a single barrel or single cylinder stove pipe thimble.

In the accompanying drawings;—The nu- 60 meral 1 designates the outside barrel or cylinder of the stove pipe thimble provided with the external rim flanges, *a*, and, *b*, at opposite ends, respectively.

The numeral 2 designates the annular head 70 or end of the stove pipe thimble which is secured to the outside cylinder 1, preferably by folding the outer portion, *c*, of said head or end over the outer portion of the rim flange, *b*, of said outside cylinder 1; the inner edge 75 of said annular head or end 2, is provided with the flange, *d*, and in this head or end 2 the register openings 4 the supplemental openings 5 and the central or stove pipe open- 80 ings 6 are formed.

7 designates an annular register which rests against and moves freely on the head or end 2, and in said register 7 the register open- 85 ings 8, the supplemental openings 9, and the central or stove pipe opening 10 are formed, which openings 8, 9 and 10 correspond with the openings 4, 5 and 6 of the head or end 2.

11 designates a cover or cap, the flange, *e*, of which is fitted to and inserted in the central or stove pipe openings 6 and 10 in said 90 head or end 2 and said register 7, respectively.

12 designates a removable annular head or end which is secured to the ring or collar 13, preferably by folding the outer portion, *f*, of said removable head or end 12 over the outer 95 portion of said ring or collar 13, and this ring or collar 13 is provided with a flange 14, which is fitted to and inserted in the end of the outside cylinder 1; and said flange 14 and said outside cylinder 1, are so constructed 100 and fitted that when said flange is inserted in the open end of said cylinder 1, their frictional contact will firmly hold them together from any possibility of accidental disengage- 105 ment.

15 designates a flange with which the inner edge of said head or end 12 is provided, and 16 designates diagonal brackets which extend from and are secured at one of their ends to said flange 15 of said annular head or end 12 and at their other ends to said flange 14 on said ring or collar 13, to brace and stiffen 110

said annular head or end 12 to permit its removal without injury. And in said removable annular head or end 12 the register openings 17, the supplemental openings 18, and the central or stove pipe opening 19 are formed.

20 designates a register in which is formed the register openings 21, the supplemental openings 22, and the central or stove pipe openings 23, and 24 designates knobs with which said registers 7 and 20 are provided, to facilitate the adjustment of said registers.

25 designates a cap or cover with which the removable head or end 12 is provided, and said cap 25, is provided with a flange 26 which is fitted to and inserted in said central or stove pipe openings 19 and 23, in said removable head or end 12 and said register 20, respectively.

20 27 designates an inner barrel or cylinder shown in Fig. 5, which is preferable to use in the case of large stove pipe thimbles to brace and stiffen the same.

In order to facilitate the formation of the 25 annular rim flanges, *a*, and *b*, on the outside cylinder 1, slits 28 are preferably formed in them as shown in Fig. 1. And to insure the holding of the inner barrel or cylinder 27 in place it may be bolted or otherwise secured 30 to the flange 15 of the head or end 12.

The assembling of the different parts of the 35 stove pipe thimble is clearly shown by the drawings, and when so assembled, said stove pipe thimble may be inserted in the ordinary or original stove pipe hole, there will be therefore no necessity for any extra or additional cutting away of the wall, ceiling or carpet; and when inserted in said stove pipe hole will not project nor will it be in the way of 40 anything; and again when the stove pipe is projected through said thimble it stiffens and strengthens and protects said thimble. And there being an annular air space between the outside cylinder 1 and the stove 45 pipe, or between said cylinder 1 and the inner cylinder 27, it will be practically impossible for the heat from the stove pipe to radiate across this annular air space and through the outside cylinder 1, to injuriously affect the 50 surrounding wall, ceiling or carpet, thus rendering this device fire proof. And this air space between the stove pipe and the outside cylinder 1, forms a passage which, when the registers 11 and 20 are open, permits the heat to pass from one apartment 55 to another, and when one end of this thimble opens into a chimney or when it is located in an outside wall, provides an exit for ventilation. And by means of the registers, the passage 60 of the heat from one compartment to another, or the ventilation may be readily, easily and instantly regulated, thus forming a perfect heat conveyer, regulator and ventilator. And when the registers are closed, 65 all possibility of the dust passing from one

compartment to the other will be avoided, thus rendering this device dust proof. And when there is no pipe in this thimble, by inserting the covers 11 and 25 in the central openings in the heads, it will be impossible 70 for the dust from one room to pass into the other. Again the supplemental openings in the heads or ends and in the registers are so arranged that when the register openings are closed, said supplemental openings in said 75 registers will be opposite the register openings in the head or end, and the supplemental openings in the head or end will be opposite the register openings in the register, this will permit currents of air to enter said air space 80 between the pipe and said outside cylinder, to further assist in preventing any excess of heat from the stove pipe from injuriously affecting the surrounding wall, ceiling or carpet. And when the stove pipe is removed from the thimble, the overhanging edge, *g*, of the cap or cover will hold the registers 20 and 7 in place. And the register openings being formed practically the same width as the air 85 space, these thimbles can be kept perfectly 90 clean and free from dust. And one end of the thimble being formed removable they can be slipped into the stove pipe hole in the chimney after the latter is built.

The heads or ends of the thimble hold it in 95 place, they do not therefore require any nails, screw nails, springs or other holding means to hold them in place. These thimbles are made any length required, they will therefore fit neatly on the walls, ceiling or 100 floors. And by ventilating into the chimney, are not affected by winds, dust or rain storms. And by permitting the heat of one 105 room to pass into another, they economize and save fuel expenses. And by having 110 double registers, one at each end, they are under instant control from either of the rooms or compartments. At the same time a simple, strong, durable inexpensive, clean, safe, and efficient device is provided.

Having thus described my invention, I 115 claim:—

1. In a device of the class described, the combination with an outside cylinder provided at each end with an external flange, and heads secured to the flanges on each end of said cylinder, one of which heads is detachable, and in each of which heads a central opening and a series of register and supplemental openings are formed, and a ring or 115 collar to which said removable head is secured, of an annular register adjacent to each head in which a series of register and supplemental openings are formed, substantially as shown and described and for the purpose 120 specified.

2. In a device of the class described, the combination with an outside cylinder, provided at each end with an external flange, heads secured to each of the flanges of said 125

cylinder, one of which heads is detachable, and in each of which heads a central opening and a series of register and supplemental openings are formed, and an inside cylinder, 5 of an annular register mounted on each head in which a series of register and supplemental openings are formed, substantially as shown and described and for the purpose specified.

3. In a stove pipe thimble, an outside 10 cylinder provided at each end with an external flange, annular heads on each end of said cylinder, each head having inner and outer flanges, the outer flanges engaging the external flanges of the cylinder, each head provided with a series of register openings and a 15 series of supplemental openings, an annular register arranged to rotate on each head and each register provided with register openings and supplemental openings, a ring or 20 collar within one end of said cylinder, and

braces secured to said ring or collar and to the inner flange of the head adjacent thereto.

4. In a device of the class described, the combination with an outside cylinder, heads secured to each end of said cylinder, one of 25 which heads is detachable, and in each of which heads, a central opening and a series of register and supplemental openings are formed, an inside cylinder, and a cap secured in the central opening of each head, of an 30 annular register adjacent to each head in which a series of register and supplemental openings are formed, substantially as shown and described and for the purpose specified.

In testimony whereof, I have signed in the 35 presence of the two undersigned witnesses.

WILLIAM B. McLEAN.
